[57] CLAIM

The ornamental design for a controller for machine tools, as shown and described.

DESCRIPTION

FIG. 1 is a bottom, front and side perspective view of a controller for machine tools showing my new design;
FIG. 2 is a front elevational view thereof;
FIG. 3 is a rear elevational view thereof;
FIG. 4 is a side elevational view thereof; and
FIG. 5 is a top plan view thereof.

*fig. 1.**fig. 2.**Fig. 3.**Fig. 4.*

Fig. 5.
